UNITED STATES PATENT OFFICE.

EDWIN M. CRAFT, OF INDIANAPOLIS, INDIANA.

DESIGN FOR A JEWELRY STONE.

Application filed September 28, 1925. Serial No. 14,926. Term of patent 14 years.

To all whom it may concern:

Be it known that I, EDWIN M. CRAFT, a citizen of the United States of America, a resident of the city of Indianapolis, county of Marion, and State of Indiana, have invented a new, original, and ornamental Design for Jewelry Stone, of which the following is a specification, reference being had to the accompanying drawings, forming a part thereof.

Fig. 1 is a top plan view of the jewelry stone.

Fig. 2 is a front elevation of a jewelry stone taken in the plane of 2—2 of Fig. 1, the dotted lines indicating a conventional base and the full lines the stone face.

Fig. 3 is an end elevation of a jewelry stone taken in the plane of 3—3 of Fig. 1, the dotted lines indicating a conventional base and the full line the stone face.

I claim:

The ornamental design for a jewelry stone as shown.

EDWIN M. CRAFT.
